(57) **CLAIM**

The ornamental design for a police badge bottle opener, as shown and described.

DESCRIPTION

FIG. 1 is a top plan view of a police badge bottle opener showing my design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a perspective view thereof; and,

FIG. 8 is a perspective view thereof showing a bottle cap being opened.

The broken lines depict environmental subject matter only and form no part of the claimed design.
